PROTECTOR MECHANISM FOR LOOMS

Oscar V. Payne, Leicester, and Elliot A. Santon,
Worcester, Mass., assignors to Crompton &
Knowles Loom Works, Worcester, Mass., a cor-
poration of Massachusetts

Application February 17, 1941, Serial No. 379,222

14 Claims. (Cl. 139—345)

This invention relates to improvements in protector mechanisms for looms and it is the general object of the invention to provide a mechanism more particularly adaptable for use on wide looms such as are used for weaving paper makers felts.

It has been customary heretofore to weld the daggers on the protector rod but when such a practice is employed repairs necessitate the removal of the protector rod and its bearings from the lay. It is an important object of our present invention to provide daggers which are formed separately from the protector rod but held to it in adjusted position for cooperation with the knock-off and bunter mechanisms.

When protector rods of considerable length are used it is customary to have several daggers between the end daggers which are located near the loomsides, and it is also usual to make the rod in several sections held together by couplings. When the shuttle boxes are at one side of the loom the actuating force for rocking the rod and the daggers comes from that end and any twist in the long rod caused by the inertia of the intermediate daggers and the couplings may prevent the daggers near the center of the loom, and those at the remote end, from being depressed quickly enough to avoid entry into their bunters. It is an important object of this invention to provide a light one piece rod without the usual couplings and relatively free from objectionable twist.

Another feature of our invention is to provide means for setting the daggers at different angular positions with respect to the rod so that each dagger can be set for proper engagement with its bunter regardless of slight variations in the heights of the several bunters.

It has been customary heretofore to transmit all of the stopping force for the lay through the protector rod, but this mode of operation, especially on long looms, is likely to bend the rod, and furthermore, because of the weight of the longer lay, the rod is subjected to considerable strain. It is a further object of our present invention so to construct the daggers which are mounted on the protector rod that the lay stopping force will be transmitted from the lay to the bunters directly through the daggers without requiring the rod to transmit all of the stopping force. In carrying this feature of our invention into effect we locate each dagger slightly in front of a force transmitting plate on the lay and between the rod bearings so that at the time of protection the rod bends slightly to permit

the dagger to have direct engagement with the plates. In this way the protector rod is spared all but a small amount of the force required to stop the lay.

With these and other objects in view which will appear as the description proceeds, our invention resides in the combination and arrangement of parts hereinafter described and set forth.

In the accompanying drawing, wherein convenient embodiments of our invention are illustrated in connection with two forms of daggers.

Fig. 1 is a front elevation of part of the lay of a wide loom showing the preferred form of our improved protector mechanism applied thereto.

Fig. 2 is a vertical section on line 2—2 of Fig. 1 showing the protector rod and the parts carried thereby in two different positions.

Fig. 3 is an enlarged detail longitudinal section on line 3—3 of Fig. 1.

Fig. 4 is an enlarged transverse section on line 4—4 of Fig. 1 showing the parts in the position they assume when a dagger engages its bunter lever at the beginning of a knocking off or stopping operation of the loom, the bunter lever and associated parts in this figure being omitted from Fig. 1.

Fig. 5 is a view similar to Fig. 4 but indicating a slight motion of the dagger relatively to the lay to effect positive engagement of the dagger with the previously mentioned force transmitting plate on the lay.

Fig. 6 is a horizontal section on line 6—6 of Fig. 4.

Fig. 7 is a diagrammatic plan view showing several daggers and associated parts, and

Fig. 8 is a view similar to a portion of Fig. 4 but showing a modified form of dagger.

Referring to the drawing, the loom lay 10 is provided at its right and left ends with shifting 40 shuttle boxes 11 and 12, respectively, which may be operated by any mechanism not shown to place any one of several weaving shuttles in active position. Each shuttle box has a binder 13 which will be in rear position with respect to the lay 45 when the associated shuttle box is empty but which will be moved forwardly when a shuttle enters the shuttle box. The protector rod 15 has each end thereof tapered, as at 16, see Fig. 3, to receive a correspondingly tapered hub 17 50 of a protector finger 18, which extends upwardly to engage the binder 13 of the actively placed shuttle box. A nut 19 on a threaded extension 20 of the protector rod serves to hold the protector finger tightly in fixed position on the protector rod. A torsion coil spring 21 having one end

thereof engaging the hub 17 and the other end fixed with respect to the lay acts to move the protector finger toward the binder and tends to rotate the rod in a left hand direction as viewed in Fig. 4. Each end of the protector rod will have one of the fingers 18 and both of the actively placed shuttle boxes must be empty to permit these fingers to move rearwardly.

The lay may be reciprocated backwardly and forwardly by means of connectors one of which is shown at 25 in Fig. 2 so that the lay moves toward and from a breast beam 26. Each end of the latter is provided with a bunter lever 27 which is normally held rearwardly by a spring plunger 28 the stem 29 of which extends rearwardly through a housing 30 fixed with respect to the breast beam and surrounded by a compression spring 31 which offers considerable resistance to forward motion of the plunger 28. The bunter levers are located in front of the shipper handles 33 to move the same rearwardly from running to stopping position when the bunter lever 27 is moved forwardly. Intermediate bunters 35 similar to the bunter levers are located at spaced intervals along the breast beam and are of the usual construction.

Except as indicated hereinafter the above described matter is of common construction and may operate in the usual manner, the shuttles S and S' shown in Fig. 2 being picked across the loom to enter one or another of the shuttle boxes and move the corresponding binders forwardly to move the protector finger 18 forwardly and rock the protector rod in a clockwise direction from the full to the dotted line position shown in Fig. 2. For a further description of the construction and operation of certain of the parts already mentioned reference may be had to the following patents: Lundgren, 1,872,994, and McGuiness, 1,029,937.

In carrying our present invention into effect we provide the forward part of the lay with a plurality of spaced bearings 40 each having a main plate 41 bolted as at 42 to the lay and having formed therewith a hub 43 in which the protector rod rotates freely. Extending to one side of each of the bearing members is a lateral extension or force transmitting plate 45 which has close contact with the front wall 46 of the wooden part 47 of the lay. These bearings are readily detachable from the lay by removal of the bolts 42.

Located at spaced intervals along the protector rod are the daggers the preferred form of which is indicated at 50 in Fig. 4. These daggers each comprise an enlarged body 51 through which the protector rod extends and a reduced front pointed knock-off end 52 positioned for engagement with the associated bunter. As shown in Fig. 4 each dagger 50 has extending vertically therethrough a locking bolt 55 having an arcuate recess 56 cut therein to fit around a portion of the protector rod 15. A tightening nut 57 and a lock nut 58 are provided for each of the lock bolts 55 to draw the latter upwardly to establish a tight holding connection between the dagger and the protector rod. By loosening the nuts 57 and 58 the angular position of the dagger may be changed with respect to the protector rod.

An important feature of our present invention resides in the construction of the rear part of each dagger, which, as shown in Fig. 5, is provided with an upwardly extending abutment having a substantially vertical face 60 extending to

a point above the protector rod and located close to but normally slightly in front of the forward face of the corresponding lateral extension or plate 45 therebehind.

5 In the modified form shown in Fig. 8 the dagger 65 has a forward end 66 for engagement with its bunter and has the rear end split as at 67 to permit clamping by a bolt 68 on the protector rod 15.

10 In setting the daggers the lay will be moved forwardly to cause the several daggers to engage their bunters and bunter levers 27 when the shuttle boxes in line with the shuttle path are empty. In this connection it should be remembered that in wide looms it is a matter of practical manufacturing difficulty to have all of the bunters at exactly the same vertical level and this is one reason for having the daggers angularly adjustable on the protector rod. The nuts 57 and 58 are then tightened to hold the daggers fixed to the protector rod in their several positions. The daggers will then be set to stop the loom unless a shuttle enters an actively placed shuttle box. When a shuttle is boxed, however, the daggers will be moved downwardly out of stopping position and the lay will continue to move forwardly. A similar setting is effected when the modified form of dagger is used.

15 Should the shuttle fail to be boxed properly the daggers will remain in their high position and as the lay moves forwardly they will engage the bunters and cause a slight bending of the protector rod between the bearings sufficient to cause engagement between the surfaces 60 of the daggers and the plates 45, after which the protector rod will not be subjected to any further bending and the whole force of stopping the lay will be transmitted from the extensions 45 through the upper part of the daggers along a line above the protector rod to the bunters. The normal gap between the surface 60 on the back of the protector daggers and the plates 45 is small so that a very slight bending of the protector rod will suffice to cause the engagement mentioned. Furthermore, the daggers are spaced sufficiently from the bearings 40 to permit this bending of the rod. By relieving the protector rod of the necessity for transmitting all of the stopping force necessary to arrest the lay we avoid those strains which might disturb the setting of the daggers on the protector rod and also bend the latter.

20 Heretofore, it has been customary either to weld the daggers to a single rod or make the rod in sections which are held together by couplings. Because of the slight variations of the heights of the bunters across the loom it was necessary to adjust each dagger and its bunter by a twisting operation when the daggers were welded to the rod and correct alignment was difficult to attain. When the sections of the rod were held together by couplings on the other hand it was found that the coupling nearest the box into which the shuttle passes was required to transmit all of the strain for moving the remaining sections extending to the opposite side. As a result of the repeated turnings of the end sections their couplings became loosened and the original alignment of the daggers was lost. Under these conditions the intermediate daggers were relatively high and would strike their bunters even though the end daggers were depressed to non-stopping position and a bending of the lay and also the breast beam of the loom resulted

even though the active shuttle entered its box. In our present invention we have eliminated the couplings by using a single rod and have also provided for adjusting the daggers without twisting the rod as is the case when daggers are welded.

Should damage occur to any dagger the bearings 40 and the other daggers between it and the nearer end of the loom can be removed after which the damaged dagger is slid endwise off the rod without taking the latter from the lay. This latter operation of course is not possible where the daggers are welded to the protector rod.

From the foregoing it will be seen that we have provided a simple form of protector rod wherein the daggers are individually adjustable on a single protector rod extending across the lay and that the daggers are located between and spaced from the protector rod bearings sufficiently to permit a slight forward bending of the rod such as will cause engagement between the surface 60 of the daggers and the extensions 45. The dagger is so constructed that a comparatively small part of the total force required to stop the lay will be transmitted to the protector rod, the major part of the stopping force being absorbed by the plates 45. It will also be noted that the stopping force is transmitted through the dagger along a line above the protector rod. Furthermore, the individually adjustable daggers simplify their alignment with the bunters with which they cooperate even though the latter because of manufacturing conditions are not always of the same level.

Having thus described our invention it will be seen that changes and modifications may be made therein by those skilled in the art without departing from the spirit and scope of the invention and we do not wish to be limited to the details herein disclosed, but what we claim is:

1. In a protector mechanism for a loom having a lay and a lay stopping bunter, a protector rod extending along and rotatable with respect to the lay, a dagger mounted on the rod and through which the latter passes, the dagger having a front end to engage the bunter, means on the lay for engagement with and normally spaced from the rear end of the dagger behind the rod, and means to mount the rod on the lay for slight bending of that part of the rod adjacent to the dagger, the dagger when engaging the bunter bending the rod and engaging the means to transmit a stopping force from the lay through the means and dagger to the bunter and said means preventing further bending of the rod by the bunter.

2. In protector mechanism for a loom having a lay and a lay stopping bunter, a protector rod extending along and rotatable with respect to the lay, a dagger mounted on the rod and through which the latter passes, the dagger having a front end to engage the bunter, means on the lay for engagement with and normally spaced from the rear end of the dagger behind the rod, and means to mount the rod on the lay for slight bending of that part of the rod adjacent to the dagger being so related to the bunter, the rod and the means that, the dagger when engaging the bunter said dagger will bend the rod and engage the means to transmit a stopping force from the lay through the means and dagger to the bunter along a line passing to one side of the rod, and said means preventing further bending of the rod by the bunter.

3. In protector mechanism for a loom having a lay and a lay stopping bunter, a protector rod

extending along and rotatable with respect to the lay, a dagger mounted on the rod and through which the latter passes, the dagger having a front end to engage the bunter, means on the lay for engagement with and normally spaced from the rear end of the dagger behind the rod, and means to mount the rod on the lay for slight bending of that part of the rod adjacent to the dagger, the dagger having a part above the rod to engage said means, the dagger when engaging the bunter bending the rod and engaging the means above the rod to transmit a stopping force from the lay through the means and dagger to the bunter along a line above the rod, and said means preventing further bending of the rod by the bunter.

4. In protector mechanism for a loom having a lay and a breast beam provided with a series of lay stopping bunters spaced therealong, a protector rod extending along and rotatable on the lay, a series of bearings on the lay for the rod and staggered with respect to the bunters relatively to the length of the lay and breast beam, daggers on the protector rod, one aligning with and for engagement with each of the bunters, each dagger having an abutting portion thereof projecting beyond that side of the rod opposite the corresponding bunter, and means on the lay for engagement with and normally spaced from said abutting portions, the daggers when engaging the bunters causing bending of the adjacent parts of the rod between the bearings and causing said abutting portions to engage said means to prevent further bending of the rod and arresting motion of the lay by forces transmitted from the lay through said means to the daggers and bunters independently of the rod.

5. In protector mechanism for a loom having a lay and a breast beam provided with a series of lay stopping bunters spaced therealong, a protector rod extending along and rotatable on the lay, a series of bearings on the lay for the rod and staggered with respect to the bunters relatively to the length of the lay and breast beam, daggers on the protector rod, one aligning with and for engagement with each of the bunters, each dagger having an abutment above the rod and projecting from the latter toward the lay, and means on the lay for engagement with and normally spaced from the abutments of the daggers, the daggers when engaging the bunters causing bending of the adjacent parts of the rod between the bearings and causing said abutments to engage said means to prevent further bending of the rod and arresting motion of the lay by forces transmitted from the lay through said means to the daggers and bunters along lines of force lying above said protector rod.

6. In protector mechanism for a loom having a lay and a breast beam provided with a series of lay stopping bunters spaced therealong, a protector rod extending along and rotatable on the lay, a series of bearings on the lay for the rod and staggered with respect to the bunters relatively to the length of the lay and breast beam, daggers on the protector rod, one aligning with and for engagement with each of the bunters, each dagger having an abutment above the rod and projecting from the latter toward the lay, and means on the lay for engagement with and normally spaced from the abutments of the daggers, the daggers when engaging the bunters causing bending of the adjacent parts of the rod between the bearings and causing said abutments to engage said means to prevent further bending of the rod and arresting motion

of the lay by forces transmitted from the lay through said means to the daggers and bunters, said means forming part of the bearings.

7. In a protector dagger for a loom having a protector rod and a bunter and a lay provided with a force transmitting element secured thereto, said dagger having a bore to surround the rod, clamp means to hold the dagger on the rod, a bunter engaging portion at one end thereof on one side of the bore, and means on the other end thereof on the opposite side of the bore to engage the force transmitting element above the bore.

8. In a protector dagger for a loom having a protector rod and a bunter and a lay provided with a force transmitting element secured thereto, said dagger having a bore between the ends thereof to receive the rod, clamp means to hold the dagger on the rod, a bunter engaging portion at one end thereof on one side of the bore, and means on the other end thereof on the opposite side of the bore to engage the force transmitting element at a point so located that a line joining the point and said bunter engaging portion passes to one side of said bore.

9. In a protector dagger for a loom having a protector rod and a bunter and a lay provided with a force transmitting element secured thereto, said dagger having a bore between the ends thereof to receive the rod, clamp means to hold the dagger on the rod, a bunter engaging portion at one end thereof on one side of the bore, and means on the other end thereof on the opposite side of the bore to engage the force transmitting element at a point so located that a line joining the point and said bunter engaging portion passes above said bore.

10. In a protector dagger for a loom having a lay provided with a protector rod and a force transmitting element, the loom having also a lay stopping bunter, said dagger having a forward finger to engage the bunter and having an enlarged rear end in the lower part of which is a bore between the ends of the dagger to receive the protector rod, said enlarged end having means to clamp the dagger on the rod and

having also a portion above the bore to engage the force transmitting element.

11. In a loom protector mechanism, a protector rod having a circular cross-section, a dagger on the rod, a bolt in the dagger extending transversely of the rod and having a concave recess through which the rod passes, and means to hold the bolt fixed with respect to the dagger with the concave part of the bolt in tight holding relation with the rod to prevent turning of the dagger relatively to the rod.

12. In loom protector mechanism, a protector dagger, a cylindrical protector rod extending therethrough, a bolt in the dagger at one side of and disposed transversely of the rod, said bolt having a concave recess through which the rod extends, and means to move the bolt relatively to the dagger and rod to draw the concave part of the bolt in tight holding relation with the rod, the rod and concave part of the rod cooperating to force the bolt into tight holding relation with the dagger to prevent turning of the dagger on the rod.

13. In loom protector mechanism, a cylindrical protector rod, a dagger through which the rod extends capable of assuming a plurality of angular positions on the rod, a bolt in the dagger disposed transversely of the rod and having a concave recess in one side thereof through which the rod passes, and means to hold the concave part of the bolt in tight holding relation with the rod in any one of said angular positions to prevent turning of the dagger on the rod.

14. In loom protector mechanism, a protector dagger, a protector rod having a curved exterior surface passing through the dagger, a member in the dagger having an inclined surface to engage said curved surface of the rod, and means to hold the member fixed with respect to the dagger with the inclined surface forced against the curved surface in tight holding relation therewith to prevent turning of the dagger on the rod.
